UNITED STATES PATENT OFFICE.

WESLEY MONROE SCOTT, OF COLUMBUS, OHIO, ASSIGNOR TO THE P.
HAYDEN SADDLERY HARDWARE CO., A CORPORATION OF OHIO.

ELEVATING-TRUCK.

SPECIFICATION forming part of Letters Patent No. 759,558, dated May 10, 1904.

Application filed July 20, 1903. Serial No. 186,307. (No model.)

To all whom it may concern:-

Be it known that I, WESLEY MONROE SCOTT, a citizen of the United States, residing at Columbus, in the county of Franklin and State 5 of Ohio, have invented certain new and useful Improvements in Elevating-Trucks; and I do hereby declare the following to be a full, clear, and exact description of the invention, such as will enable others skilled in the art to which 10 it appertains to make and use the same.

This invention, relating more especially to cars or trucks having vertically-movable platforms for use in brick-yards, machine-shops, and other places where heavy loads are to be 15 transported and raised or lowered, has for its object the provision of an improved, simple, cheap, and easily-operated device of this kind.

The invention is embodied in the construction hereinafter described, the particular features of novelty being pointed out in the claims. 20

In the accompanying drawings, Figure 1 is a side elevation partially in section. Fig. 2 is an end view. Fig. 3 is a detail of the sector and pinions and the shaft to which they are 25 secured.

1 designates the stationary longitudinal sills, which extend between the axles 2 and are supported on boxes 3, in which the axles turn. Bolted on the sills above the axles are four 30 hollow standards 4, one at each corner of the truck. The members of each pair of standards at the ends of the truck are preferably cast with a connecting cross-beam 4^a to brace the standards at their bases and afford a sup- 35 port for a worm-shaft hereinafter referred to.

Sliding vertically in each standard is a rack-bar leg 5, secured to or supporting at its upper end the platform 6, upon which the pallet containing brick or other article to be lifted 40 is placed. Journaled transversely of the truck and to each pair of the standards 4 is a shaft 7, having keyed thereon at each end a pinion 7^a and at its middle a sector 7^b of some- 45 what longer radius than the pinions. The pinion 7^a engages the rack-bar legs 5, and the sectors are engaged by worms 8^a of the same pitch on a shaft 8, journaled longitudinally of the car on the cross-beams 4^a. The corre-

sponding sides of the hollow standards 4 are open to permit engagement of the pinions 7^a 50 with the legs 5.

The worm-shaft 8 is furnished with a handled wheel 9, by means of which the sectors can be operated.

The operation is as follows: By turning the 55 hand-wheel 9 in the proper direction the sectors are oscillated in one direction or the other according to the direction in which the shaft 8 is turned, thus imparting a rotary movement to the pinion and a rectilinear vertical move- 60 ment to the legs 5, whereupon the platform is raised or lowered, as the case may be. Because the radius of the hand-wheel and sectors 7^b is large as compared with that of the pinions 7^a the application of slight power to the hand- 65 wheel 9 will lift a heavy load on the platform. With this construction it will also be observed that the power is exerted uniformly whatever be the position of the platform.

The use of a worm-shaft 8 in connection 70 with the sectors obviates the necessity of employing pawls and ratchets to lock and prevent the return of the platform after it is raised. With the present construction the platform is locked at any point to which it is 75 elevated and may be lowered instantly without first manipulating ratchet-pawls.

While the device shown and described is especially intended for use in brick-yards, it will also be useful in other places where heavy 80 articles are to be transported and raised or lowered.

Some slight deviations from the construction shown in the drawings can be made. For example, I see no special reason why the fixed 85 platform might not in some cases be omitted and a palette supported directly on the upper ends of the rack-bar legs. In this case, however, the palette becomes the platform.

What I claim, and desire to secure by Letters Patent, is—

1. In an elevating truck or car, the combination with the truck-frame of standards, rack-bars sliding therein, a platform or frame supported on the upper ends of said rack-bars, 95 shafts containing pinions to engage the rack-

bars, sectors of greater radius than said pinions on said shafts, and a worm-shaft to engage and operate said sectors.

2. In an elevating truck or car, the combination with the truck-frame of the standards located at the four corners of the truck-frame, rack-bars sliding vertically in said standards, a platform supported on the upper ends of said rack-bars, shafts transverse the truck containing pinions to engage the rack-bars, toothed sectors of greater radius than said pinions on said shafts, and a worm-shaft extending longitudinally of the car to engage and operate said sectors.

15 3. In an elevating truck or car, the combination with the truck-frame of the standards

located at the four corners of the truck-frame, cross-beams connecting them, rack-bars sliding vertically in said standards, a platform supported on the upper ends of said rack-bars, transverse shafts containing pinions to engage said rack-bars, toothed sectors of greater radius than said pinions on said shafts, and a worm-shaft journaled longitudinally of the car on said cross-beams to engage and operate said sectors.

20 In testimony whereof I affix my signature in presence of two witnesses.

25 WESLEY MONROE SCOTT.
